Specification for Design.

Patented Aug. 10, 1920.

Application filed January 21, 1916. Serial No. 73,480. Term of patent 14 years.

To all whom it may concern:

Be it known that I, FREDERICK R. EAGLESFIELD, a citizen of the United States, residing at Niles, in the county of Berrien and State of Michigan, have invented a new, original, and ornamental Design for Automobile-Bumpers, of which the following is a specification, reference being made to the drawings, forming a part thereof.

Figure 1 is a plan view of an automobile bumper showing my new design.

Fig. 2, is a cross section of the same.
Fig. 3, shows it applied to an automobile.
I claim:—

The ornamental design for an automobile bumper, substantially as shown.

FREDERICK R. EAGLESFIELD.
